UNITED STATES PATENT OFFICE.

JAMES V. WASHBURN, OF WATERBURY, CONNECTICUT.

DESIGN FOR A SAFETY-PIN.

SPECIFICATION forming part of Design No. 31,432, dated August 22, 1899.

Application filed July 29, 1899. Serial No. 725,541. Term of patent 14 years.

To all whom it may concern:

Be it known that I, JAMES V. WASHBURN, a citizen of the United States, residing at Waterbury, in the county of New Haven and State 5 of Connecticut, have invented and produced a new and original Design for a Safety-Pin, of which the following is a specification, reference being had to the accompanying drawing, forming a part thereof.

o In the drawing I have represented my new design for a safety-pin by an elevation.

The leading or essential feature of my design consists in the curved or approximately semicircular bar *a*.

5 The design of the safety-pin comprises the

curved or approximately semicircular bar *a*, the shield *b* at one end thereof, the eye-bend *c* at the other end thereof, and the pointed pin-bar *d*.

What I claim as new is—

The design for a safety-pin as herein shown and described.

In testimony whereof I have signed my name to this specification in the presence of two subscribing witnesses.

JAMES V. WASHBURN.

Witnesses:

GEO. T. PINCKNEY,
M. C. RYER.
